SHOE AND METHOD OF MAKING THE SAME

Karl Engel, Lynn, Mass., assignor to United Shoe Machinery Corporation, Paterson, N. J., a corporation of New Jersey

Application December 30, 1932, Serial No. 649,503

8 Claims. (Cl. 12—142)

This invention relates to improvements in the manufacture of shoes. In one aspect it consists in an improved shoe of the moccasin type. In another aspect it consists in an improved method of shoemaking in accordance with which shoes of the moccasin type may be advantageously produced, although various steps or characteristics of the method may be usefully employed in the manufacture of shoes of other types.

In the manufacture of moccasins and shoes of the moccasin type as heretofore practiced, considerable difficulty has been encountered in smoothly working over the marginal part of the upper, particularly about the forepart of the shoe, since the length of the periphery of the shoe is substantially less than the length of the periphery of the flat blank. There is, accordingly, a pronounced tendency of the upper stock to pucker or gather when its margin is made to conform to the lesser periphery of the shoe, that is, to a vamp insert or toe piece. To overcome this tendency to pucker and in order to produce a smooth forepart, a great deal of hand work has been necessary and this is not only of an arduous character but requires considerable skill on the part of the shoemaker. This problem is solved in accordance with the present invention by employing a continuous band of upper material about the forepart of the shoe to form the side walls thereof. Such a relatively narrow blank may be readily conformed to the convex contour of the periphery of a last and the upper and lower longitudinal edges of the band turned inwardly without objectionable puckering to conform to the periphery of a sole piece on the one hand and a vamp insert on the other hand. That is, the relatively narrow band may be conformed to the peripheral contour of the last and then relatively flat inserts or filler pieces may be secured to the inturned longitudinal edges and utilized in completing both the bottom of the shoe and the toe portion of the vamp.

The sole piece may be conveniently stitched to the margin of the upper band off the last, for example, by a straight needle machine adapted to form a zigzag stitch uniting the lower marginal portions of the upper band and the sole piece in edge butting relation. Such an operation may be rapidly performed and does not require shoemaking skill or experience on the part of the operator.

In uniting the upper marginal portion of the band to the vamp insert, I have found a very satisfactory union may be formed by beveling the corresponding marginal portions to thin edges at

the junction of the upper band and the vamp insert and then stitching the bevelled edges together. After stitching the upper band and the vamp insert together, the upper band and the vamp insert are supported from the inside but without lasting tension. Subsequently, the last may be inserted and a final shaping operation imparted to the forepart. When the meeting edges of the band and vamp insert are thus beveled and cemented together, the seam permanently uniting them is passed through thicker portions of the band and vamp adjacent to their thin edges and tends to shape the material outwardly of the seam into a V-shaped rib whose vertex is the line of juncture of the thin edges of the two parts, and thereby impart to the shoe the characteristic moccasin appearance.

My invention may be practiced in the manufacture of a welt shoe with particular advantage in that the welt strip may be secured to the lower edge of the band of upper material in such a manner that the inner edges of both pieces register. This step may be effected in several ways, as, for example, by stitching with a straight needle machine before the upper is brought to the last. Where this is done, the assembled welt and band of upper material may be at the same time united to the margin of the sole or bottom filler piece. This may be conveniently effected by a zigzag seam and, if desired, the welt strip may be additionally secured by a separate seam passing through it and the upper outside the zigzag stitching.

The features and advantages of my invention will be best understood and appreciated from the following description of one specific manner in which the shoemaking method may be carried out, with examples of several embodiments of the product. In the accompanying drawings:

Fig. 1 is a view in perspective of the forepart of a shoe illustrating the step of uniting the upper band with the vamp insert.

Fig. 2 is a view in perspective, on a reduced scale, showing the forepart of a shoe and portions of a stitching machine adapted for stitching the upper band and vamp insert to each other.

Fig. 3 is a view in side elevation, partly in section, of the completed shoe.

Fig. 4 is a fragmentary view in cross section of the shoe shown in Fig. 3, illustrating the stitching.

Fig. 5 is a view in perspective of the partially completed shoe in inverted position.

Fig. 6 is a view in perspective illustrating the operation of securing together the upper band and sole piece.

Fig. 7 is a view similar to Fig. 5, showing an upper made up without a welt; and

Fig. 8 is a fragmentary view in cross section of a shoe made without a welt.

In carrying out my invention, a band 18 of upper leather or the like is first cut or died out in size and shape to form the forepart of the particular shoe in hand. The band 18 is of sufficient length to make up the walls of the entire forepart of the shoe, extending rearwardly substantially to the heel-breast line. The band 18 is of sufficient width to form the upright side walls of the forepart, that is to say, it is of such width that its upper edge 12 in the finished shoe is inturned somewhat over the upper face of the last and its lower edge 14 is inturned somewhat beneath the bottom of the last. A band thus shaped is represented in Fig. 4 of the drawings.

In carrying out the invention in the manufacture of a welt shoe, a welt strip 22 is brought into face-to-face engagement with the lower margin of the upper band 18, the edge faces of the two pieces are brought into registration, and are butted against the edge face of a sole piece 28 somewhat smaller than the last bottom. The welt strip 22 and the upper band 18 may then be united to the margin of the sole piece 28 by a zigzag seam 24 or otherwise secured in butting relation. The sole piece 28 corresponds in thickness substantially to the combined thickness of the band 18 and welt 22 or, as suggested in Fig. 5, the margin of the welt or the margin of the sole piece or both may be skived or beveled so that the thickness of the welt and band will equal that of the sole piece. I prefer to employ a zigzag stitch, such as that herein shown, because it may be sewn with a straight needle machine at high speed and while the parts are in condition to be flattened out by the presser foot at the sewing point. Such an operation may be performed in the stitching room and does not require the exercise of any particular shoemaking skill. In Fig. 6, the operation of securing an upper band 18 to a sole piece 28 is shown, and in this case the welt strip is omitted, as I propose in certain embodiments of my invention.

Preparatory to attaching the vamp insert 16 to the upper inturned edge 12 of the band 18, this edge is preferably beveled at substantially a 45° angle to a thin edge at its outer surface and the marginal edge of the insert 16 is correspondingly beveled. Having secured the lower edge of the band 18 as above outlined, a filler 29 approximating the shape of the last is inserted in the forepart for the purpose of supporting the upper edge 12 of the band 18 and the marginal edge of the vamp insert 16 while they are brought into registration and secured together by cement. The contour of the filler 29 thus acts as a surface gage for locating the meeting edges of the shoe parts in registration and supporting them in such position without imparting any stretching thereto.

When the adjacent edges of the band 18 and the vamp insert 16 have been united by cement, they may be permanently stitched together with a lockstitch seam 18 sewn by a curved needle machine of the construction suggested in Fig. 2 or by any other machine suitable for this purpose. As illustrated, the machine is provided with a presser roll 40 mounted to rotate freely upon the end of a curved arm 42 by which the roll may be conveniently positioned within the shoe behind the sewing point. A pair of slotted work clamps 44 are arranged to engage the outer surface of the work and cooperate with the roll 40 in se-

curely holding the work in position for the awl and needle. The awl and needle are both curved and arranged to swing about the same axis of movement. The awl is not shown in Fig. 2, but is arranged to move upwardly, perforating the work from the side nearest the machine, and then feeding the work toward the left into alignment with the path of the needle 48 which enters the work from above, moving in a needle guide 49. A rotary shuttle disposed in a shuttle case 46 is located adjacent to the path of the needle and a looper 50 adjacent to the needle 48 serves its usual purpose in forming the lock stitch seam 18 which permanently unites the parts of the vamp.

The quarter 26 may be sewn to the rear ends 15 of the band 18 at any convenient time in the manufacture of the shoe, preferably immediately after the formation of the lock-stitch seam 18, and this operation is effected with the assistance of a straight needle machine before the upper is placed 20 upon the last. The shoe in this condition is represented in Fig. 5 of the drawings. Having completed the upper in the manner above explained, a last 38 may now be forced into the shoe, stretching the upper and imparting the desired shape 25 thereto. Preparatory to inserting the last 38, a heel-seat piece 34 may be inserted within the upper and the heel-seat then lasted by working the lower margin of the quarter, counter and lining over the bottom of the last and tacking 30 them to the heel-seat piece 34 which, it will be understood, rests upon the metallic heel plate 32 of the last. The construction of the heel-seat is in accordance with well-known methods of shoe-making, as illustrated in Fig. 3.

Having now completed and shaped the upper to the last, an outsole 36 may be stitched to the welt 22 by a line of stitching 38 formed by an outsole stitcher of commercial type or any other machine suitable for this purpose. The outsole 36 40 may extend for the full length of the welt 22 and the heel-seat of the shoe may be secured by heel-seat nails driven through the outsole, the in-turned margins of the quarter 26 and the slip sole 34. It will be apparent that the shoe thus 45 formed has, in respect to the attachment of the outsole, all the advantages of a welt shoe.

If desired, the welt may be entirely dispensed with and an outsole secured to the shoe bottom by any desired method of through-and-through 50 fastening. A sewed shoe of this character is shown in Figs. 7 and 8, where the lower longitudinal edge 14 of the band 18 is shown as butted and stitched by a zigzag line of stitching 24 to the margin of a sole piece 120, without the presence 55 of a welt strip. In completing a shoe of this kind, the outsole 136 is placed upon the shoe bottom thus formed and stitched by a seam 138 directly to the inturned margin of the upper band 18 which is adjacent to the insole 120.

It will be apparent from the foregoing description that the difficult operation of smoothly conforming a flat vamp of large dimensions to the smaller contour of a finished shoe has been obviated by employing a narrow upright band in 65 the periphery of the forepart and supplementing this with an insert which substantially covers the forepart. Moreover, the employment of such a band, which may be cut to fit its place in the shoe without substantial stretching, permits the 70 welt strip to be registered with its edge as a preliminary step of the shoe-making method instead of being secured at an indeterminate line depending to some extent on the degree of stretch in the vamp, as in prior commercial practice. 75

Having thus described my invention, what I claim as new and desire to secure by Letters Patent is:

1. A method of making shoes, which consists in registering one edge of a band of upper leather with an edge of a welt strip, securing said registered edges to the margin of a sole piece, supporting the other edge of said band and simultaneously securing the margin of a vamp insert thereto, and subsequently inserting a last in the upper and stitching an outsole to the welt strip. 5
2. A method of making shoes, which includes the steps of shaping a band of leather to form the upright peripheral walls of the vamp, beveling the upper longitudinal edge of said band, supporting said edge about its contour without stretching the band, cementing a beveled edge vamp insert to the edges of the band while so supported, and then stitching together the adjacent edges of the band and insert. 10
3. A method of making shoes, which consists in shaping a narrow band to constitute the peripheral walls of the forepart of a shoe, cement coating the upper longitudinal edge thereof, inserting a filler within the forepart to support the upper cement-coated edge of the band without substantially stretching the same, and then uniting to said cement-coated edge a vamp insert completing the forepart of the shoe. 15
4. A method of making shoes, which consists in shaping a band to constitute the peripheral walls of the forepart of a shoe, inwardly beveling the upper edge of the band and applying cement thereto, temporarily supporting the cemented edge from the inside, butting a correspondingly beveled and cemented vamp insert to the edge of the band while so supported, and then stitching through the band and insert within the butted line to form a V-shaped ridge. 20
5. A method of making shoes, which consists in shaping a band of upper material to form the walls of the forepart, applying cement to the upper longitudinal edge of the band, temporarily supporting the cemented edge by a filler member which supplies a gage for locating a vamp insert, butting the edges of the band and vamp insert while both are positioned by the filler, removing the filler, and stitching the butted edges together while their line of juncture is locally supported from inside the forepart. 25
6. A method of making shoes, which consists in shaping a band of definite width to constitute the walls of the forepart without widthwise stretching of the band, securing a welt strip to the lower edge of the band in edge-registering relation, temporarily supporting the upper edge of the band, butting the edge of a vamp insert thereto and lightly attaching the same while the band and vamp insert are temporarily supported against collapsing inwardly, securing the butted edges by a line of stitching, inserting a last, and stitching an outsole to the welt. 30
7. A shoe of the mocassin type having a vamp which comprises a substantially upright band of upper material with its upper longitudinal margin turned inwardly and stitched to a centrally located insert, an insert shaped to fit the contour of the lower longitudinal edge of said band and forming a part of the shoe bottom, and an outsole stitched to the margin of the band outside said bottom insert. 35
8. A shoe of the mocassin type having a vamp which comprises a substantially upright band of upper material with its upper longitudinal margin turned inwardly and stitched to a centrally located insert and its lower longitudinal margin turned inwardly and secured to the edge of a shoe-bottom insert, and an outsole stitched to the lower inturned margin of said band. 40

KARL ENGEL.
